UNITED STATES PATENT OFFICE.

HARRY R. BENTRUP, OF ST. LOUIS, MISSOURI, ASSIGNOR TO SIEBER PRODUCTS MANUFACTURING COMPANY, OF ST. LOUIS, MISSOURI, A CORPORATION OF MISSOURI.

LOOSE-LEAF BINDER.

Application filed August 16, 1926. Serial No. 129,418.

This invention relates to loose leaf binders of the type in which the leaves are retained in position by tapes or flexible leaf-retaining devices that extend through slots or openings in the rear edge portions of the leaves.

One object of my invention is to provide an inexpensive loose leaf binder of the type referred to which is of such design that the 10 tapes can be kept taut enough to prevent the leaves from sagging when the binder is arranged on edge with the back piece of the cover presented upwardly.

Another object is to provide a loose leaf 15 binder of the tape type in which the back piece of the cover lies close to the rear edges of the leaves, thereby enabling the hinged side members of the cover to be spread out flat or substantially horizontally 20 on a supporting surface.

And still another object of my invention is to provide a loose leaf binder of the tape type, which is of such design that it is not necessary to use two opposed leaf-clamping 25 members on opposite sides of the bundle of leaves, thereby enabling the leaves to be opened farther or spread out more than is possible with a tape binder of the kind in which two leaf-clamping members lap over 30 the edge portions of the leaves a considerable distance. Other objects and desirable features of my invention will be hereinafter pointed out.

To this end I have devised a binder, 35 which, in its simplest form, consists of tapes or flexible leaf-retaining devices arranged in slots or holes in the rear edge portions of the leaves and connected at one end to an anchoring means located at one side of the 40 bundle of leaves, and a securing means located at the other side of the bundle of leaves composed of a member provided with slots through which the tapes pass and cams or rockable clamping devices that are 45 adapted to be forced into said slots so as to bind the tapes against the edges of the slots. In the preferred form of my invention herein illustrated the binder comprises a cover composed of a back piece and two side members 50 hinged or connected together in such a way as to permit said side members to swing freely relatively to said back, and an anchoring means and securing means of the kind previously referred to carried by the side 55 members of the cover.

Figure 1 of the drawings is a perspective view of a loose leaf binder constructed in accordance with my invention, with one of the side members of the cover folded back so as to illustrate the anchoring means to 60 which the tapes are permanently attached.

Figure 2 is a plan view, illustrating the other side member of the cover folded back, and showing the securing means that is used to hold the tapes taut. 65

Figure 3 is a detail sectional view, taken on the line 3—3 of Figure 2; and

Figure 4 is a perspective view, illustrating one of the anchoring devices.

Referring to the drawings, which illustrate the preferred form of my invention, A designates the back piece of the cover of the binder, and B and C designate the two side members of the cover, which are hinged or connected to said back piece in such a way that they can swing freely relatively to same. The leaves x are retained in position by a plurality of tapes or other suitable flexible leaf-retaining devices D that pass transversely through the bundle of leaves through holes or slots in the rear edge portions of the leaves. Said tapes are permanently connected at one end to an anchoring means carried by the cover member B and composed of anchoring devices E rockably mounted on a shaft 1 that extends longitudinally of the cover member B through a tubular bearing 2 located on the inner side 75 of said cover member at the extreme rear edge of same. The particular shape or form 80 of the anchoring devices E is immaterial, so far as my broad idea is concerned, but I prefer to use anchoring devices of substantially angle shape in outline, each of which 85 comprises a horizontally-disposed leg 3 that laps over the bundle of leaves, and a vertically-disposed leg 4 that projects into the bundle of leaves through the holes in the leaves that receive the tapes D, as shown in Figure 3. As shown in Figure 4, the horizontal leg of each anchoring device is provided with ears that are bent over one end 90 of the tape so as to attach the tape to said leg. 95

The securing means previously referred to that is used to hold the tapes taut is preferably composed of a member F of plate-like form that is rockably mounted on a shaft 5 which extends longitudinally of tubular bearings 6 carried by the cover member 100 105 110

C and arranged on the inner side of same adjacent its rear edge. The plate member F has slots 7 in same through which the tapes D pass, and clamping devices G are rockably mounted on the shaft 5 in such a way that they can be forced into the slots 7, so as to bind or clamp the tapes tightly against the edges of said slots, as shown more clearly in Figure 3, each of the clamping devices G comprising a tubular portion 8 through which the shaft 5 passes, a depending gripping portion or clamping portion 9 of less width than the slots 7, and a finger piece 10 that is adapted to be used either to move the clamping member into operative position or to disengage said member from the tapes, so as to release the same.

When it is desired to open the binder it is only necessary for the user to pull upwardly on the free end portions of the tapes D in a direction to exert upward pressure on the finger pieces 10 of the clamping devices G, thereby withdrawing the gripping portions 9 of said clamping devices from the slots 7 in the member F and releasing the tapes. When it is desired to bind the tapes, the cover of the binder is arranged in the position shown in Figure 3, i. e., with the side member B resting upon a supporting structure and the side member C folded back, thereby enabling the user to exert a pull on the tapes D in a direction to stretch said tapes taut and force the member F downwardly, so as to clamp the leaves together. Thereafter, the clamping devices G are rocked in a direction to force the portions 9 of same into the slots 7 in the member F, thus causing the tapes to be clamped tightly against the edges of said slots. Preferably, the side member B of the cover is provided on its inner side with pockets 11, as shown in Figure 2, for receiving the end portions of the tapes D.

A loose leaf binder of the construction above described is inexpensive to manufacture and the tapes of same can be kept taut enough to prevent the leaves from sagging when the binder is arranged on edge with the back piece of the cover presented upwardly, due to the fact that it is not equipped with a tape-winding mechanism arranged between the back piece of the cover and the rear edges of the leaves, as is the general custom in loose leaf binders of the tape type. Another advantage of such a binder is that the side members B and C of the cover can be spread out flat in substantially the same horizontal plane with the rear edges of the leaves arranged in close proximity to the supporting surface on which the cover rests. And still another advantage of such a binder is that the bundle of leaves are not clamped between two opposed leaf-clamping members that lap over

the leaves a considerable distance. In other words, in my binder the leaves are held tightly clamped together by tapes that are connected to anchoring devices E of substantially angle shape in outline whose vertical legs project into the holes or slots in the leaves through which the tapes pass, thereby enabling practically the full width of the leaves to be used for a writing surface. Anchoring devices E of the kind above described not only increase the area of the writing surface of the leaves, but they also tend to prevent the tapes from tearing the leaves when the tapes are tightened, because the horizontal legs 3 of same insure a direct pull on the tapes at a point a considerable distance inwardly from the rear edges of the leaves.

Having thus described my invention, what I claim as new and desire to secure by Letters Patent is:

1. A loose leaf binder, comprising tapes or flexible leaf-clamping members that pass through holes in the leaves, anchoring devices arranged at one side of the bundle of leaves to which said tapes are connected, 90 said anchoring devices being of substantially angle-shape and arranged with the vertical legs of same projecting into the bundle of leaves, and clamping devices arranged at the opposite side of the bundle of leaves for 95 securing said tapes after they have been drawn taut.

2. A loose leaf binder provided with a cover that comprises side members, hinged or pivotally mounted anchoring devices carried by one of said side members and provided with portions that project into holes in the binding edge of the leaves, tapes connected to said anchoring devices and arranged in said holes in the leaves, a member carried by the other side member of the cover and provided with slots through which said tapes pass, and clamping devices provided with portions that are adapted to be forced into said slots so as to clamp the 110 tapes against the edges of said slots.

3. A loose leaf binder provided with a cover that comprises a back piece and hinged side members, substantially angle-shaped anchoring devices pivotally mounted on one 115 of said side members and arranged so that their horizontal legs lap over the leaves and their vertical legs project into holes in the bundle of leaves, tapes connected to said anchoring devices and arranged in said holes 120 in the leaves, a hinged part on the other side member of the cover provided with slots through which the tapes pass, and rockable clamping devices provided with gripping portions that are adapted to enter the slots 125 in said part and clamp the tapes against the edges of said slots.

HARRY R. BENTRUP.
